CUFF LINK

Benjamin J. Strauss, Los Angeles, Calif.

Application July 2, 1948, Serial No. 36,739

2 Claims. (Cl. 24—97)

1

This invention has to do generally with cuff links and particularly with a cuff link provided with a pivotally mounted head adapted normally to holding the cuff link in a shirt cuff. While the invention involved is particularly useful for cuff links, it is contemplated that the same may be usefully applied in other articles and devices where it is desired to pivotally connect two members so that the same can be yieldably held in a selected position.

An object of this invention is to provide a novel cuff link having a pivotally mounted retaining head adapted to stay or remain in adjusted position.

A further object of the invention is to provide a pivotal construction for joining two elements in a manner such that they will be yieldably held in any of several selected positions.

Another object is to provide a cuff link construction of the above type of pivotally mounted head in which the working parts are substantially obscured from view.

A still further object is to provide a cuff link embodying a pivotally mounted head with means for releasably holding the head in selected position which is of simple construction having few parts and can be easily manufactured.

These and other objects will be apparent from the drawing and the following description thereof. Referring to the drawing, which is for illustrative purposes only:

Fig. 1 is a side elevational view of a cuff link embodying the invention;

Fig. 2 is a plan view of the cuff link of Fig. 1;

Fig. 3 is a view similar to Fig. 1, but showing the retaining head in another position;

Fig. 4 is a plan view of the link as shown in Fig. 3;

Fig. 5 is an enlarged fragmentary sectional view on the line 5—5 of Fig. 1;

Fig. 6 is an enlarged sectional view on the line 6—6 of Fig. 5;

Fig. 7 is a section on line 7—7 of Fig. 4;

Fig. 8 is a perspective view of the retainer head;

Fig. 9 is a perspective view of the spring element;

Fig. 10 is a perspective view of the shank of the cuff link.

More particularly describing the invention, reference numeral 10 indicates the ornamental head of the cuff link which may take any desired form and, which, for purposes of illustration, has been shown in the form of a circular disc. Extending from the rear side of the head 10 is a

shank generally indicated by numeral 11. The shank comprises two legs 12 joined by a connecting portion 13 which is attached to the head 10 in any suitable manner as by means of brazing or soldering such as indicated at 14. The legs are connected at their outer ends by a bridge generally indicated by numeral 15. The bridge includes a bridging portion 17, which connects the legs and a block-like cam element or portion 18, which is provided with an end cam face 19. The portion 18 of the bridge is of less width than the distance between the two legs 12, with the result that a space 20 is left between each leg 12 and the portion 18.

The cuff link is provided with a retaining head generally denoted by numeral 22. This head is formed to provide side walls 23 and end walls 24, as well as the main wall section 25. Each of the end walls 24 is provided with a recess forming a ledge 27, the ledges receiving the ends of a flat spring 28.

The side walls 23 of the retainer head are each provided with an apertured mounting ear 30 and the ears are received in the spaces 20 located between the legs of the shank and the portion 18 of the bridge. A pin 31 serves to pivotally connect the shank and the retainer head. When the parts are assembled, the flat cam surface 19 of the bridge bears against the spring 28 which is deflected slightly as shown in Fig. 6. With this construction it will be apparent that the retainer head will be yieldably held in the position in which it is shown in Figs. 1 and 6 by the cooperating spring and cam surface on the bridge.

In order to provide for over 90° pivotal movement of the retainer head to facilitate insertion of the cuff link through the button holes of a cuff, the side walls 23 of the retainer head are each provided with a pair of notches 34. Thus when the retainer head is turned from the position in which it is shown in Fig. 1 to the position of Fig. 3, the notches 34 receive the bridging portion 17 of the bridge as best shown in Fig. 7. When in this position the spring lies along and contacts 45 the side of the bridge and thereby serves to yieldably hold the parts in this position. In this connection, it may be pointed out that the bridge is somewhat thicker at its outer end than at its inner end with the result that the sides of the bridge converge somewhat permitting the retainer head to pivot slightly more than 90°, however the bridge may be made the same thickness throughout if desired.

Although the invention has been particularly shown and described, it is contemplated that vari-

ous changes and modifications can be made without departing from the scope of the invention as defined in the claims which follow.

I claim:

1. A cuff link comprising an ornamental head, a shank extending from the head, said shank including a pair of spaced legs connected adjacent their ends by a bridge, said bridge being spaced inwardly of the ends of the legs, and having a leg bridging portion and a block-like cam portion of less width than the distance between said legs extending toward the end of said legs from said bridging portion and terminating in a flat face, an elongated hollow retainer head of a width such that it is receivable between said legs, said head having a pair of mounting ears respectively received between said cam portion of the bridge and said legs, a pin pivotally connecting said legs and said ears, and a flat spring mounted in said retainer head in slightly flexed condition and in engagement with said cam face.

15

20

2. A device as defined in claim 1 in which the width of said retainer head is less than the distance between the legs of the shank and in which the sides of said retainer head are notched to receive the bridging portion of said bridge when the retainer head is turned to lie with its longitudinal axis substantially parallel to the longitudinal axis of said shank.
